CLAIM

The ornamental design for a mesh clamp, as shown and described.

DESCRIPTION

FIG. 1 is a top plan view of a mesh clamp showing our new design;

FIG. 2 is a right side view thereof;

FIG. 3 is a front view thereof;

FIG. 4 is a left side view thereof;

FIG. 5 is a bottom view thereof;

FIG. 6 is a perspective front view thereof;

FIG. 7 is a perspective rear view thereof;

FIG. 8 is a rear view thereof;

FIG. 9 is a top plan view of the mesh clamp of FIGS. 1-8 without shading showing our new design thereof;

FIG. 10 is a right side view thereof;

FIG. 11 is a front view thereof;

FIG. 12 is a left side view thereof;

FIG. 13 is a bottom view thereof;

FIG. 14 is a perspective front view thereof;

FIG. 15 is a perspective rear view thereof; and,

FIG. 16 is a rear view thereof.
